UNITED STATES PATENT OFFICE.

JOHN SAMUEL POTTER AND ALEXANDER TOUGH, OF NIAGARA FALLS, ONTARIO, CANADA.

DESIGN FOR A PENNANT.

47,894.

Specification for Design.

Patented Sept. 28, 1915.

Application filed May 19, 1915. Serial No. 29,250. Term of patent 7 years.

To all whom it may concern:

Be it known that we, JOHN SAMUEL POTTER and ALEXANDER TOUGH, subjects of the King of Great Britain, and residents of the city of Niagara Falls, in the county of Welland, in the Province of Ontario, Canada, have invented a new, original, and ornamental Design for a Pennant, of which the following is a specification, reference being had to the accompanying drawing, forming part thereof.

The figure is a plan view of a pennant illustrating our new design.

We claim:

The ornamental design for a pennant, as shown.

JOHN SAMUEL POTTER.
ALEXANDER TOUGH.

Witnesses:

JEAN WILLS,
W. A. McDOWELL.
